OIL BURNER

Filed Jan. 9, 1926

FIG. 1.

FIG. 2.

Patented Dec. 7, 1926.

1,609,385

UNITED STATES PATENT OFFICE.

GEORGE WILLIAM SMITH, OF BUFFALO, NEW YORK, ASSIGNOR TO MAUDE SMITH,
OF BUFFALO, NEW YORK.

OIL BURNER.

Application filed January 9, 1926. Serial No. 80,279.

My invention relates to improvements in oil burners of the usual type which include a burner and means for supplying a mixture of oil and air to the burner, and the object of the invention is to construct means whereby oil and air are supplied at a predetermined constant ratio. A further object of the invention is to devise means whereby the rotations of the fan which constitutes the air blower control the supply of oil fed to the combustion chamber of the burner, and a still further object of the invention is to provide for the thorough atomization of the oil and a complete mixing thereof with the air supplied for combustion.

My invention consists of an oil burner constructed and arranged all as hereinafter more particularly described and illustrated in the accompanying drawing in which:—

20 Fig. 1 is a front elevational view of my oil burning apparatus showing the means for supplying air and oil to the burner which is contained interiorly of the furnace, the top portion of which is broken away.

25 Fig. 2 is a side elevational view of my device showing the combustion chamber and part of the air supply conduit in section, a fragmentary portion of the interior of the furnace being shown.

30 Fig. 3 is an enlarged sectional detail showing the means whereby the air blower controls the supply of oil to the burner, and

Fig. 4 is a detail of the upper portion of the oil controlling needle valve which is 35 threaded into a sleeve for adjustment purposes.

Like characters of reference indicate the corresponding parts in the different views.

1 is a platform suitably mounted upon a plurality of legs 2 and adapted to be positioned exteriorly of the furnace and 3 is a blower fan casing positioned centrally upon the upper face of the platform and secured thereon. 4 is an electric motor positioned 40 upon one side of the blower fan casing 2, being seated upon the bracket 5 which extends from the casing. The motor is adapted to rotate the blower fan in the casing 3, being suitably coupled to the spindle 6 upon 45 which the blower fan is mounted.

50 7 is the combustion chamber which is positioned upon a pedestal 8 interiorly of the furnace. The combustion chamber 7 is preferably of pot shape and constructed of carborundum or a similar material, and 9 is a

baffle plate behind which is situated a gas pilot jet 10 for keeping the baffle plate hot when the burner is not in operation. In the pot 7 and opposite the baffle plate 9 an orifice 11 is situated, and 12 is a sleeve adapted 60 to be inserted into such orifice and project into the pot. The interior of the sleeve 12 is so constructed that a throat 13 is formed, its narrowest part being approximately in the center of the sleeve and gradually increasing in diameter towards each end. 14 is a second sleeve situated interiorly of and centrally in the sleeve 12, its outer end being bell mouthed and gradually decreasing in diameter as it approaches the inner end of 70 the sleeve 13 as illustrated in Figure 2.

15 is the oil supply pipe, its inner end extending upwardly into the center of the sleeve 12 and passing into the sleeve 14, its end being open and adapted to permit the 75 oil to enter such sleeve, and 16 is the air supply conduit which extends from the air blower casing 3 to the outer end of the sleeve 13, being held in relation thereto by the collar 17 which extends around the ends of 80 both the sleeve conduit and pipe.

For regulating the supply of oil in a constant fixed relation to the supply of air, I provide the device illustrated in section in 85 Figure 3 which I shall now describe.

Upon the opposite side to the motor 4 on the blower fan casing 3, a cylindrical casing 20 is positioned, being mounted upon and secured to a bracket 21 which extends from the adjacent face of such blower fan casing. 90 The blower fan spindle 6 is provided with an extension spindle 22 which passes through the casing 20 being supported centrally in the casing in the bearings 23 in the ends thereof. In the casing 20 is positioned a 95 rotatable ball governor consisting of a pair of governor balls 24 connected by pairs of arms 25 and 26 to collars 27 and 28 which are mounted upon the spindle 22, the collar 27 being secured to the spindle, and the collar 28 and attached grooved collar 29 being 100 slidable on the spindle.

30 is a spiral spring encircling the spindle 22 and inserted between the collars 27 and 28. At the bottom of the outer end of the casing 20, I provide an outwardly extending 105 passage 31 which connects with a vertical cylindrical casing 32, the lower end of the casing being open. 33 is a valve seating member adapted to be secured on the bottom 110

of such casing by means of the nut 34, and 35 is a vertical passageway extending upwardly through the valve seating member 33, its upper end constituting a seat for the 5 tapered needle valve 36 which extends upwardly through the casing 32, the tapered end being inserted into the passageway 35. Upon the upper end of the needle valve 36, an internally threaded sleeve 37 is positioned, the needle valve being threaded thereinto and the sleeve adapted to project through the upper end of the casing 32, being 10 slideable in an orifice 38, and 39 is a spiral spring encircling the sleeve 37, being 15 inserted between the inner face of the upper end of the casing 32 and a flange 40 on the lower end of the sleeve 37.

41 is an angularly positioned arm in the casing 20, being pivotally mounted in proximity to its lower end upon a pin 42 which extends across the lower portion of the casing. The upper end of the arm 41 is bifurcated and extends about the grooved collar 29 having a pair of inwardly extending pins 25 43 on its bifurcated ends which project into the groove in the collar. The lower end of the arm 41 is bent at an angle to the main portion and projects beyond the pin 42, its outer end bearing on the upper surface of 30 one end of an arm 44 which is horizontally mounted intermediately of its length upon a pin 45 which extends across the passageway 31, the other end of the arm 44 being bifurcated and adapted to straddle the needle 35 valve 36, its upper face being in contact with the lower face of the flange 40. 46 is a lock nut threaded upon the upper end of the needle valve 36 and adapted to screw down upon the top of the sleeve 37.

40 A cylindrical chamber 47 is formed integrally with, and positioned beside the vertically disposed casing 32, the interior of the cylindrical chamber 47 being connected to the interior of the casing 32 by means of a 45 horizontal passage 48. Internally of the chamber 47 I position a cylindrical float 49 through which a needle valve 50 freely extends, the lower or pointed end of the needle valve entering an orifice 51 in the lower face 50 of the casing, such orifice communicating with a cylindrical chamber 52 in which a cylindrical oil sieve 53 is positioned and 54 is the oil feed pipe, one end of which connects with the chamber 52 and the other end 55 is a cap positioned upon the top of the chamber 47, and 56 are a pair of downwardly extending lugs upon the ends of which a pair of arms 57 are pivoted intermediately of 60 their length, the upper ends of the arms being pivotally connected to the upper end of the needle valve 50, the lower ends carrying counter-weights 58 which rest upon the top of the float 49. 59 is an extension upon 65 the upper face of the cap 55 into which the

top of the needle valve enters when it moves upwardly.

The operation of my device is as follows:—

Upon desiring to operate the burner, the cock 60 in the oil feed pipe 54 is opened, 70 thus permitting oil to flow downwardly into the chamber 52, passing from thence into the chamber 47, the needle 50 being in the raised position under the influence of the counter-weights 58 on the arms 57. As the 75 oil enters the chamber 47 the float 49 will gradually rise until it comes in contact with the counter-weights 58 lifting them upwardly, and thus moving the upper ends of the arms 57 and the needle valve downwardly, and cutting off the oil supply to the chamber 47 when a predetermined quantity of oil has entered therein.

When the cock 60 is opened the switch controlling the motor 4 is manually closed, 80 thus starting the motor which rotates the blower fan, spindle 22, and the governor which is mounted thereon. After the oil enters the chamber 47 it flows therefrom through the passageway 48 into the lower portion of the casing 32, the needle valve being in the closed position as shown in Figure 3. As the governor balls 28 are rotated by the spindle 22 they swing outwardly and through the medium of the arms 26 connecting the balls with the collar 28, such collar and the connected collar 29 will move along the spindle in the direction of the blower fan, swinging the arm 41 in an anti-clockwise direction. As the lower end of the arm moves it will depress the outer end of the arm 44 with the consequent upward movement of the other or inner end and as the inner end presses against the flange 40 of the sleeve 37, the sleeve and needle valve 105 26 will be moved upwardly, thus opening the entrance to the passageway 35 and permitting the oil in the casing 32 to flow downwardly through the pipe 15 into the burner.

As the spindle 22 and the governor balls 24 reach their normal rotative speed, the needle valve 36 will be lifted a predetermined degree, and a predetermined quantity of oil will be admitted to the burner. Should the rotative speed of the spindle be increased due to fluctuations in the electric current driving the motor, the governor balls 28 will swing outwardly in a greater arc and the arm 41 will have a further movement, thus further lifting the needle valve 36 and permitting a greater quantity of oil to pass to the burner, the quantity of oil being in the same ratio as the increased draft of air supplied by the greater speed of the blower fan. Should however, the rotative speed of the motor become reduced the speed of the blower fan and the volume of air therefrom will also become reduced and the governor balls 28 will swing in a smaller arc, moving the collars 28 and 110 115 120 125 130

29 in the opposite direction with the consequent clock-wise movement of the arm 41 and a resultant partial downward movement of the needle valve 36 causing a reduction 5 in the oil supply to the burner.

If it is desired to adjust the needle valve 36 in its relation to the passage 35, the lock nut 46 on top of the sleeve 37 is loosened and the needle valve turned either up or down 10 in the sleeve 37 according to the adjustment required. When the correct adjustment is attained the lock nut 46 is turned down to its normal position on the top of the sleeve 37, thus locking the needle valve in the 15 sleeve. On reference to Figure 3 of the drawings it will be seen that by the provision of the oil control float valve mechanism that I have provided a means for preventing undue flooding of the needle valve 20 casing 32 when such needle valve is partially closed and the passage of the oil to the outlet passageway 35 is restricted, if the float valve mechanism were not provided the oil 25 would flood such casing and finally enter and flood the casing 20 in which the governor balls are contained. It will therefore be seen that the float valve controlling the admission of oil through the orifice 51 prevents the oil in the casing 32 from ever 30 reaching the passage 31 leading to the casing 20 as the bottom of such float is always at a lower level than the bottom of such passageway. By the provision of the float 35 valve the leakage of oil is obviated even though the cock 60 is left open when the burner is not working as the float will automatically close the needle valve 50 and thus seal the oil contained in the chamber 52 and oil feed pipe 54.

40 From the above description it will be apparent that I have devised an oil burner of very simple construction which can be very readily adapted for use in either hot air, water or steam heating systems, the predetermined ratio of oil and air delivered to the burner being constant, the supply of oil increasing or decreasing in ratio to the supply of air. This outstanding feature of my device insures a practically perfect combustion 45 at all times irrespective of any fluctuations of the electric motor with the consequent variations of the blower fan speed. It has been found in experimental tests, that an oil burner constructed as described in the foregoing 50 description can be left operating without attention for periods covering two or three weeks, a uniform temperature being maintained at all times.

55 What I claim as my invention is:

60 1. In an oil burning apparatus, the combination of a burner, means for supplying oil to said burner, means for supplying air to said burner and having an operating shaft, a governor on said shaft, a receptacle 65 in which said governor is contained, a pair

of communicating oil receiving receptacles one of which communicates with the governor containing receptacle, a needle valve in the oil receiving receptacle which communicates with the governor containing receptacle, a 70 lever communicating with the governor for actuating the needle valve and extending through the communication between the said needle valve receptacle and the governor receptacle, and a float actuated valve in the 75 second oil receiving receptacle for preventing the oil level in the needle valve containing receptacle from ever reaching the conduit through which the lever passes between said receptacle and the governor containing 80 receptacle.

2. In an oil burning apparatus, the combination of a burner, means for supplying oil to said burner, means for supplying air to said burner and having an operating 85 shaft, a governor on said shaft, a pair of communicating oil receiving receptacles in the oil conduit, one of said receptacles communicating with a third receptacle in which is contained the governor on the operating 90 shaft, and a float actuated valve in one of the oil receiving receptacles for controlling the oil level in the other oil receiving receptacle and preventing such oil from ever passing 95 therefrom into the governor containing receptacle.

3. In an oil burning apparatus, the combination of a burner, means for supplying oil to said burner, means for supplying air to said burner, and having an operating shaft, a governor on said shaft, a pair of communicating oil receiving receptacles in the oil conduit, a float controlled valve in one of said receptacles for controlling the flow of oil thereinto, a needle valve in said other oil 100 receiving receptacle, one end of said valve projecting outwardly through an orifice in the receptacle, an adjustable sleeve on said needle valve which also projects through said orifice, a swingable lever actuated by the 105 governor and co-acting with the sleeve on the needle valve, and means whereby said needle valve may be adjusted in said sleeve in relation to its seating whereby the flow of oil from the needle valve containing oil 110 receiving receptacle can be manually adjusted.

4. In an oil burning apparatus, the combination of a burner, means for supplying oil to said burner, means for supplying air to said burner and having an operating 115 shaft, a governor on said shaft, an oil receiving receptacle in the oil conduit, a needle valve in said oil receiving receptacle for controlling the flow of oil therefrom, a receptacle in which the governor is contained, a communicating passage leading from said 120 receptacle to the oil receiving receptacle and communicating therewith intermediately of the height, a swingable lever actuated by the 125 governor for controlling the needle valve, 130

and extending from the governor through oil receiving receptacle for maintaining the
the communicating passage into the oil re- oil at a predetermined level in the first-men-
ceiving receptacle, a second oil receiving re- tioned oil receiving receptacle wherein such 10
ceptacle communicating through a passage oil level never reaches the communicating
5 with the first mentioned oil receiving re- passage through which the governor actu-
ceptacle in the vicinity of its lower end, and ated lever extends.

GEORGE WILLIAM SMITH.
